UNITED STATES PATENT OFFICE.

EDWIN H. BELL, OF CHICAGO, ILLINOIS.

TIE-PLATE.

1,219,224.

Specification of Letters Patent. Patented Mar. 13, 1917.

Application filed October 9, 1916. Serial No. 124,503.

To all whom it may concern:

Be it known that I, EDWIN H. BELL, a citizen of the United States, and a resident of Chicago, in the county of Cook and State of Illinois, have invented certain new and useful Improvements in Tie-Plates; and I do hereby declare that the following is a full, clear, and exact description thereof, reference being had to the accompanying drawings, and to the letters of reference marked thereon, which form a part of this specification.

This invention relates to an improvement in tie plates and consists of the matters hereinafter described and more particularly pointed out in the appended claims.

The object of the invention is to produce a tie plate which shall combine with a maximum of efficiency in the performance of its intended function, a minimum of metal and a maximum of rigidity against buckling, so that it will withstand the bending strain to which it is subjected.

These and other advantages of my improved tie plate will appear as I proceed with my specification.

In the drawings:

Figure 1 is a perspective view of a tie plate made in accordance with my invention.

Fig. 2 is a bottom plan view of the tie plate.

Fig. 3 is a view illustrating a longitudinal section through the tie plate, in a plane indicated by the line 3—3 of Fig. 1.

Fig. 4 is a view illustrating a transverse section through the tie plate, in a plane indicated by the line 4—4 of Fig. 1.

Referring now in detail to that embodiment of my invention illustrated in the accompanying drawings, 5 indicates the tie plate as a whole, which, as shown, is oblong in plan as usual. The plate has a flat bearing face 6 on its top side, which is adapted for engagement with and is of substantially the width of the bottom side of the rail base. At one end of the bearing face 6 is provided the usual transversely extending, rail-abutting flange or shoulder 8. The top side of the plate at its ends and beyond the rail-abutting flange or shoulder 8 and beyond the opposite end of the bearing face 6 is preferably inclined or tapered downwardly toward the ends of the plate.

On the bottom surface of the tie plate are provided transverse, tie-engaging flanges or

ribs 9, 9, preferably two as shown. Said ribs thus extend parallel to the rail-abutting shoulder 8 on the top face of the tie plate and one of them is preferably located immediately below the rail-abutting shoulder 8, while the other is spaced from it a distance substantially equal to the width of the rail base.

In that part of the bottom surface of the tie plate between the transverse ribs 9, 9, there are formed a plurality of parallel, arcuate undulations, grooves or depressions 10, which extend parallel to the length of the tie plate (that is, to say, at right angles to the tie engaging ribs 8, 8) and which are comparatively flat or shallow. The arcuate surfaces of the several grooves intersect in a plurality of parallel lines in the plane of the bottom of the tie plate, thus presenting a plurality of parallel ribs 11 extending parallel to the length of the plate and at right angles to the rail abutting shoulder. Said ribs thus run with the grain of the wood of the tie when the tie plate is in use.

The bottom of the end parts of the plate beyond the ribs 9, is flat and is adapted to rest on the top surface of the tie.

The tie plate thus described is manifestly one that it is easy to manufacture in that it is capable of being readily rolled from a billet. Having a flat top bearing face for engagement with the rail base, without grooves or depressions, it is apparent that water will not collect and stand between the rail base and the plate so as to rust and thus gradually destroy and disintegrate the top of the plate.

The undulations or grooves 10 below the rail engaging surface of the plate, diminish the weight of the plate without destroying its strength and this particularly, because said undulations or grooves are arranged transversely of the plate or at right angles to the line in which the plate tends to buckle or bend, and thus provide flat arches to resist this strain.

The bottom of the tie-plate will naturally, under the pressure and pounding of the rail, become slightly depressed into the surface of the tie. Since the grooves 10 run in the direction of the length of the plate, that is, parallel to the tie, the ribs between them extending parallel to the fibers of the wood of the tie, will embed themselves between said fibers and will act to prevent the plate from

- creeping in the direction of the rail, without damaging or distorting the fibers of the wood. The tie engaging ribs 9, 9 and the other ribs 11, will together produce a seat 5 for the tie plate in the top surface of the tie which will prevent movement of the tie plate on the tie either in the direction of the length of the rail or in a direction transverse thereto and will assist in holding the rail to gage.
- 10 I claim as my invention:
1. A tie plate having a flat, rail-bearing face and a bottom, tie-engaging surface, said tie-engaging surface including two longitudinally spaced tie-engaging ribs extending 15 transversely of said plate and projecting below its bottom surface and the bottom surface of said plate between said ribs, being formed to provide a plurality of parallel, flattened, arcuate undulations or grooves ex- 20 tending in the direction of the length of said plate, the surfaces of said undulations or grooves intersecting to provide a plurality of tie-engaging ribs extending in the direction of the length of said tie plate and located 25 in the plane of the bottom surface thereof.
  2. A tie plate having a flat, top, rail-bear-

ing face and a bottom, tie-engaging surface, said tie plate being provided with a transverse, rail-abutting shoulder at one end said rail-bearing face, and said tie-engaging surface including two longitudinally spaced tie-engaging ribs extending transversely of said plate and projecting below its bottom surface, one of said ribs being located low said rail abutting shoulder, and a bottom surface of said plate between said ribs being formed to provide a plurality of parallel, flattened, arcuate undulations or grooves extending in the direction of the length of said plate, the surfaces of said undulations or grooves intersecting to provide a plurality of tie-engaging ribs the bottom surface of said plate extending in the direction of its length.

In testimony that I claim the foregoing as my invention I affix my signature in presence of two witnesses, this 5th day of October, A. D. 1916.
